UNITED STATES PATENT OFFICE.

EDWARD R. MASON, OF DES MOINES, IOWA.

GRINDSTONE.

SPECIFICATION forming part of Letters Patent No. 292,242, dated January 22, 1884.

Application filed November 12, 1883. (No model.)

To all whom it may concern:

Be it known that I, EDWARD R. MASON, of Des Moines, in the county of Polk and State of Iowa, have invented an Improvement in 5 Grindstones, of which the following is a specification.

My invention relates to the method of bushing the square eye of a grindstone, and adapting it for the insertion of a detachable crank-shaft or arbor, for which United States Letters Patent were issued to me August 7, 1883, No. 282,546; and my object is to dispense with the screw-thread and nut required on the end of the thimble or sleeve for fastening 15 the detachable flange to the sleeve and stone.

My improvement consists in loops or extensions on the inside faces of the flanges or disks that are placed over the eye and cement in the grindstone, as hereinafter fully set 20 forth, in such a manner that the loops or extensions will be embedded in the cement, and fastened thereto when it is hard, to retain the flanges firmly fixed over the eye and center of the grindstone, and at all times in proper position for the reception of a detachable thimble, 25 sleeve, crank-shaft, or arbor.

Figure 1 of my accompanying drawings is a perspective view of a disk having loops projecting from its inside face. Fig. 2 is a transverse section of a disk having fastening devices formed integral therewith. Fig. 3 is a transverse section of a stone having its eye bushed by means of my disks, having fastening devices adapted to be embedded in cement. 35 Jointly considered, these figures clearly illustrate the construction and operation of my complete invention.

A is a disk, that is flat on its inside face, and preferably convex and ornamented on the 40 outside by annular swells or beads around its central perforation, through which a thimble, sleeve, crank-shaft, or arbor is to be passed.

b b (shown in Fig. 1) are wrought-metal loops, that have their ends bent at right angles 45 and placed in the mold to be embedded in the molten metal, when the disk is cast, in such a manner that they will be permanently fixed to the disk to project at right angles therefrom.

50 c c (shown in Fig. 2) are modified forms of

fastening devices formed integral with the disk A. Any form of loop, hook, or projection having an enlarged or bent end may be adopted to accomplish the result contemplated.

To apply my disks, having fastening devices on their inside faces, to a stone to bush its square eye, as required, to prepare it for the reception of a detachable thimble or sleeve, crank-shaft, or arbor, I simply place one of the 55 disks on a suitable support, and then put a grindstone over it in such a manner that it will be concentric with the disk and the projecting fastening devices inside of the square eye, and then insert a detachable thimble or 60 sleeve, short shaft, or former in the perforation of the disk, to extend vertically through the center of the eye. I next fill the cavity and eye with suitable cement, and then cover it with a second disk and press the projecting 65 fastening devices on the inside face of the disk into the cement, and retain all the parts in place until the cement has hardened and bound the two disks on the opposite sides of the stone firmly together, as required, to finish 70 the stone for the market and practical use.

By thus forming and applying disks and bushing the square hole in a grindstone for the reception of a thimble or sleeve, crank-shaft, or arbor, the labor and expense required 75 for cutting screw-threads and putting on nuts, or passing screw-bolts through the eye and disks or flanges of thimbles, as heretofore practiced, will be dispensed with and the work of mounting and operating a stone facilitated.

I am aware that metal bushing-plates having teeth projecting from their inside faces to prevent the plates from turning have been inserted within the eye of a grindstone and 80 embedded in cement to form a central bearing for a detachable crank-shaft; but my manner of forming loops or hooks on the inside faces of disks to prevent them from outward movement, as well as from turning, as required, to 85 retain the disks or flanges firmly fixed over the square eye of a grindstone, and against its opposite sides to cover the eye and cement, is novel and greatly advantageous.

I claim as my invention—

1. As a new article of manufacture, a disk for bushing grindstones, having loops or hook-shaped fastening devices projecting from its inside face, that are adapted to be embedded 5 and fastened in cement, for the purpose set forth.

2. The combination of two disks, having loops or hook-shaped fastening devices pro-

jecting from their inside faces, with a grindstone by means of cement, in the manner set forth, for the purposes specified.

EDWARD R. MASON.
